LIQUID DISPENSING APPARATUS

John W. Haley, Cranston, R. I., assignor to The Narragansett Brewing Company, Cranston, R. I., a corporation of Rhode Island

Application July 17, 1934, Serial No. 735,643

6 Claims. (Cl. 40—8)

My invention relates to improvements in liquid dispensing apparatus, particularly of a type adapted to dispense liquid from large containers not normally visible by the purchaser. While my invention may be employed in dispensing of any type of liquid, it is particularly adapted for the dispensing in glasses, of malt, or other fermented liquors, such as beers, ales, wines, cider, etc. Hitherto, in the dispensing of beer or like liquids the container itself is usually not visible to the purchaser, but normally rests in the cellar and has the pipe leading therefrom to the usual tap or die faucet usually mounted so as to be visible to the purchaser on or near the top of the usual serving counter or bar. An object of my invention therefore is to substantially insure that the purchaser of refreshing liquid at a bar, soda fountain, or otherwise from large containers through a tap or faucet is substantially assured of getting the trade marked or otherwise branded beverage he desires. To achieve this result, I preferably provide a handle for operating the usual tap valve having trade mark or other brand indicia thereon so that the customer may designate the exact tap from which he desires his beverage drawn and as an additional safeguard to the customer and also to the seller of beverage in the retail establishment, I preferably provide in combination therewith an irremovable seal or tag attached to the pipe leading from the specific dispensing tap on which the trade mark or branded insignia is displayed to the barrel and imprint on said seal or tag a like or similar trade mark or designation so that a quick glance in the basement or place where the pipe leading from the tap may be attached to its liquid container, will insure that the correct tap is attached to the right barrel. This supplemental tag or seal also furnishes to the manufacturer a check on whether his trade marked or branded tap is properly connected to his trade marked or branded liquid container. While any suitable type of a tag may be employed I preferably employ a tag similar to that in use for sealing freight cars, comprising a flat disk of moldable metal having two diametric holes therein, a wire securable around the pipe and having the ends thereof projecting through the diametric holes in said disk with said disk then compressed by a suitable tool or die having trade mark indicia thereon to compress said disk tightly around said wires and imprint the trade mark indicia thereon to irremovably secure said wire

around said pipe and I preferably provide such an irremovable trade marked or branded disk in combination with the trade marked tap handle on the dispensing counter I preferably employ.

Further features of my invention relate to my improved handle member for said tap valve detachably securable to the bail or other handle member which normally projects from the tap valve. For this purpose I preferably provide a molded handle member having a base provided with suitable means for securing it to said bail or other handle member, preferably an integral neck and a partially spherical gripping and display portion preferably integrally mounted on said neck, including at least a hemispherical portion on one side thereof for operative gripping in the palm of the hand and a circular preferably countersunk preferably convex socket, preferably of substantially the circumference of said spherical portion on the other side thereof, preferably tilted upwardly relative to the vertical and having an annular projecting rim and a cooperating convex plate preferably of substantially the size and configuration of said socket having identifying trade mark indicia thereon secured within said socket so that the outer edges thereof are preferably protected by said annular rim.

Further objects of my invention therefore are to provide a handle for tap valves having a hemi-spherical portion for easily gripping by the hand and at the same time having a relatively flat portion which may be moved to a position so that it may be identified from the front of the serving counter and having trade mark or other identifying indicia thereon.

A further object of my invention is to provide said side bearing the trade mark indicia, whether the trade mark indicia be separately engraved on the detachable plate or otherwise, tilted upwardly relatively to the vertical so that the plate or otherwise trade marked or branded portion of said handle may be readily at all times observable by a customer standing in front of the serving counter to identify his desired brand of beverage.

A further object of my invention is to provide a metal or other type of rigid plate which may be secured in the countersunk socket therefor and protected by the annular rim thereof against removal and protecting the lithographed or other matter thereon from most of the handling necessary in operating the tap valve.

These and such other objects of my invention as may hereinafter appear will be best understood from a description of an embodiment thereof, such as is shown in the accompanying drawing.

In the drawing, Fig. 1 is a sectional view taken through a usual bar having a standard type of a beer tap mounted thereon and showing how the beer barrel mounted in the cellar is normally connected thereto and illustrating my improved tap valve handle attached thereto and my improved tag connected to the pipe end adjacent to the beer barrel.

Fig. 2 is a front elevation of the bar shown in Fig. 1 illustrating in the center a tap valve handle constructed in accordance with my invention and bearing identifying, preferably trade mark indicia.

Fig. 3 is a perspective view of the seal I preferably employ prior to being compressed around the pipe end.

Fig. 4 is a sectional view through the pipe end showing my improved seal or tag in attached position thereon.

Fig. 5 is an enlarged view showing my improved tap valve handle attached to the tap.

Fig. 6 is a front elevation of my improved tap valve handle and showing underneath it a portion of the usual bail for operating the valve.

In the drawing, wherein like characters of reference indicate like parts throughout, I have shown my invention as applied to a standard type of beer or ale dispensing apparatus including the beer tap 10 located adjacent the usual serving counter or bar 12 having the usual rail 14 in front thereof and connected to the usual beer barrel or liquid container 16. I have shown in Fig. 1 a modern type of such an equipment, including the steel barrel 16 normally stood on end in the cellar, the plug 18 including the pipe 20 (shown in dotted lines) extending to the bottom of the barrel and the annular air inlet pipe 22 discharging at the top of the barrel suitably connected by the pipe 24 to a suitable compression pump (not shown). The usual pipe 26 projects upwardly from said plug 18 and through the serving counter itself, has the coil 28 therein within the ice chamber 30 of said serving counter 12 and has the upper end 32 thereof connected to the tap 10. In most equipments the upper end 32 of the pipe 26 projects inwardly and the tap 10 is connected thereon so as to project inwardly therefrom over the shelf 34 on which the glass 35 is adapted to rest while the tap is run. The tap 10 includes the usual spout 36, the valve (not shown) and in most instances a bail 38 for operating the tap valve which terminates in the flat upper end 40 usually having the threaded bolt 42 projecting upwardly therefrom. It is obvious, however, that insofar as my invention is concerned the tap 10 itself may be mounted on top of the bar 12, or in any convenient position adjacent the top of said bar 12 so that my improved tap valve handle 44 may be readily observable by a customer standing in front of the bar or serving counter 12.

My invention therefore includes as liquid dispensing apparatus in combination with the liquid container or beer barrel 16 and serving counter or bar 12, the tap 10 having the spout 36 discharging near the counter top 13, the handle 44 for operating said tap valve having the preferably trade marked indicia 46 thereon, the pipe 26 leading from said tap and having an end 27 detachably securable to a succession of liquid containers 16 bearing the desired identifying and

trade mark indicia and a seal or tag 48 preferably bearing like or similar trade mark indicia 50 connected to said pipe end 27 so that the pipe end may be attached to the containers 16 having trade mark indicia only corresponding to the indicia 50 on said tag 48 and the indicia 46 on said tap valve handle. Thus as hitherto explained, in order to insure to the customer that he is getting his desired trade marked or other branded beverage I provide in combination a tap handle constructed so as to bear trade mark indicia and an irremovable seal also bearing said trade mark indicia on the pipe detachably connected to the container 16 for the trade marked or otherwise branded liquid.

While my improved tag 48 may be constructed in any suitable manner, I preferably construct it as follows: I provide a flat disk 52 of moldable metal having the two parallel substantially diametric holes 54 therein. I provide a short wire 56 having the loop portion 58 adapted to be secured around said pipe and having the two ends 60 thereof project through said holes 54. I then suitably attach said loop 58 around the pipe end 27 and tighten the ends 60 by pulling them through said holes 54 to bring the disk 52 immediately adjacent the pipe. I then by means of a suitable compressible die or tool having the trade mark indicia molded therein compress the disk 52 so to completely and compactly squash it around the wires so as to irremovably seal the wires immediately adjacent the pipe end 27 and to compress the disk with the trade mark indicia 50. Thus in use once the seal or tag bearing the trade mark indicia 50 has been attached to the pipe end 27 by the manufacturer's agent in the installation, anyone can see by inspection if a pipe end 27 bearing the trade mark indicia 50 is suitably connected to a beer barrel or container 16 containing the desired trade marked beverage and as the pipe 26 bearing the trade mark indicia 50 is preferably connected to the tap handle 44 bearing similar or like trade mark indicia 46, it is obvious that my invention provides means to insure to the manufacturer and consumer that the consumer is actually getting the trade marked beverage through the proper dispensing apparatus.

As stated hitherto, further features of my invention relate to my improved type of tap valve handle 44 and as stated hitherto said handle is preferably constructed so it may have a semi-spherical portion for the ready handling or operation thereof in use and suitable, preferably protected trade mark indicia 46 thereon preferably tilted upwardly relative to the vertical so that it may be more readily observed by a customer standing in front of the bar 12. My preferred embodiment of tap valve handle 44 is preferably constructed as follows. It preferably includes an integrally molded base 64, preferably integral neck 65 and partially spherical gripping and display portion 66, preferably integrally mounted on said neck 65. The base 64 is preferably provided with the central bolt receiving inverted socket 68 projecting upwardly therein for screwing on said bolt 42. The partially spherical gripping and display portion 66 is integral with said neck 65 and includes at least a hemi-spherical portion 70 on one side 70 thereof for operating or gripping in the palm of the hand or by the fingers and a circular countersunk socket 72 preferably convex and preferably of substantially the circumference of the spherical portion 70 on the other side thereof 75

preferably tilted as at 74 upwardly relative to the vertical and having the annular projecting rim 76. I preferably suitably attach within said socket, a plate 78 bearing the preferably trade 5 mark indicia 46 on the outer surface thereof and preferably also convex and preferably of the size and configuration of said socket 72 secured within said socket so that the outer edges of the plate 78 are protected by said annular 10 rim 76 exterior of said socket 72 in said portion 76. I also preferably construct said bail 38, base 64 and neck 65 of such a size and so tilt said socket 72 and cooperating plate 78 that said plate 78 and indicia 46 may be readily observed 15 by a customer standing in front of said serving counter 12 as of substantially the size of said tap valve handle as is apparent in Fig. 2. I preferably employ the plate 78, preferably constructed of metal or other suitable material so that the 20 desired trade mark or brand indicia 46 may be suitably lithographed, or otherwise formed thereon and so that the entire surface thereof may be enameled if desired except for the lithographing so as to display an attractive trade 25 mark side of my improved tap valve handle.

It is apparent that if desired the plate 78 may be countersunk in the socket 72 to be protected by the rim 76 so as to protect the plate on its trade marked face against wear caused by the 30 operation of the handle. If desired the handle 44 may be merely provided with a flat surface, preferably tilted relative to the vertical so as to be more readily observable in front of the bar, bearing the trade mark indicia thereon 35 without departing from the spirit of my invention.

Occasionally taps are provided in which the spout 36 discharges towards the front of the bar and in this event by means of suitable washer means 80 my improved tap valve handle 46 be mounted on the bail 38 so that the trade 40 mark face 46 thereof may be visible from the front of the bar.

It is obvious therefore that I have provided 45 certain novel improvements in liquid dispensing apparatus including the combination of a trade marked tap valve handle and a trade marked pipe end at all times secured to said trade marked tap handle, and novel features in the 50 specific construction of the means I employ for securing the desired trade mark to the tap handle and the desired trade mark to its co-operating pipe end in the manner explained above with the attendant advantages portrayed 55 above.

It is understood that my invention is not limited to the specific embodiment shown and that various deviations may be made therefrom without departing from the spirit and scope of 60 the appended claims.

What I claim is:

1. A molded handle member for a tap valve having a base having a central bolt receiving threaded socket projecting upwardly therein, an 65 integral neck and a partially spherical gripping and display portion integrally mounted on said neck, comprising at least a hemi-spherical portion on one side thereof for operative gripping in the palm of the hand, and a circular counter-sunk convex socket of substantially the circum-

ference of said spherical portion on the other side thereof tilted upwardly relative to the vertical and having an annular projecting rim and a cooperating convex plate having identifying trade mark indicia thereon substantially the 5 size and configuration of said socket secured therein so that the outer edges thereof are protected by said annular rim.

2. A molded handle member for a tap 10 having a base an integral neck and a partially spherical gripping and display portion integrally mounted on said neck, including a partially spherical portion on one side thereof for operative gripping in the palm of the hand and a circular countersunk socket on the other side 15 thereof tilted upwardly relatively to the vertical and a cooperating plate having identifying indicia thereon substantially the size and configuration of said socket secured therein.

3. A molded handle member for a tap valve 20 having a base, an integral neck and a partially spherical gripping and display portion integrally mounted on said neck including a partially spherical portion on one side thereof for operative gripping in the palm of the hand and a 25 circular countersunk socket on the other side thereof and having an annular projecting rim and a cooperating plate having identifying indicia thereon substantially the size and configuration of said socket secured therein so that 30 the outer edges thereof are protected by said annular rim.

4. A molded handle member for a tap valve having a base an integral neck and a partially spherical gripping and display portion integrally 35 mounted on said neck including at least a hemi-spherical portion on one side thereof for operative gripping in the palm of the hand and a circular countersunk socket of substantially the circumference of said spherical portion on the 40 other side thereof tilted upwardly relative to the vertical and having an annular projecting rim and a cooperating plate having identifying indicia therein substantially the size and configuration of said socket secured therein so that 45 the outer edges thereof are protected by said annular rim.

5. A molded handle member for a tap valve having a base having a central bolt receiving threaded socket projecting upwardly therein, an 50 integral neck and a partially spherical gripping and display portion integrally mounted on said neck including at least a hemi-spherical portion on one side thereof for operative gripping in the palm of the hand and a circular counter- 55 sunk socket on the other side thereof and a co-operating plate having identifying indicia therein of substantially the size and configuration of said socket secured therein.

6. A molded handle member for a tap valve 60 having a base having a central bolt receiving threaded socket projecting upwardly therein an integral neck and a partially spherical gripping and display portion integrally mounted on said neck including a partially spherical portion on 65 one side thereof for operative gripping in the palm of the hand and a relatively flat trade mark indicia bearing portion on the other side thereof tilted upwardly relative to the vertical.

JOHN W. HALEY.
